UNITED STATES PATENT OFFICE

ADOLPH LANGSNER, OF CHICAGO, ILLINOIS, ASSIGNOR TO EUGENE DIETZGEN COMPANY, OF CHICAGO, ILLINOIS, A CORPORATION OF DELAWARE

DEVELOPING APPARATUS

Application filed February 8, 1928. Serial No. 252,717.

My invention relates to an improved developing apparatus for developing light sensitive material, such as paper or the like, by means of an alkaline developing agent preferably in gaseous form such, for instance, as ammonia gas. The invention also includes the process of developing the light sensitive material.

One of the objects of my invention resides in providing an improved process for developing light sensitive material by bringing the same in proximity to relatively fine portions or drops of liquid developing medium which pass through the air adjacent the developing medium or its path of travel whereby such drops give off developing gas for accomplishing the development of the light sensitive material.

Yet another object of my invention resides in the means whereby the developing gas is produced or evolved in the developing chamber by dropping relatively small particles of liquid developing medium through the air and adjacent the path of travel of the light sensitive material whereby the gas evolved from the falling drops or particles will come into contact with the light sensitive material and develop it.

Yet another object of my invention resides in the provision of an apparatus for creating a falling spray-like arrangement of liquid ammonia in the developing chamber adjacent the path of travel of the light sensitive material for causing the evolved gases from the falling spray or drops to develop the material and particularly in means for collecting the drops or spray and re-circulating them so that the liquid developing medium is constantly re-used.

Still another object of my invention resides in the manner in which the traveling light sensitive material is fed between the paths of travel of the falling drops of liquid developing medium whereby the material is subjected to the action of the developing gases evolved therefrom from both sides.

Yet another object of my invention resides in combining with the foregoing mechanism a means for slightly wetting the light sensitive material prior to subjecting it to the ac-

tion of the developing gases such as ammonia gas whereby to expedite and accelerate the developing action.

Still another object of my invention resides in the compact arrangement of the developing cabinet and whereby the various chambers in the developing cabinet are isolated the one from the other so as to preclude the passage of the developing gas from one chamber to the other while at the same time permitting the feed or passage of the light sensitive material through the chamber in proper sequence.

Yet another object of my invention resides in the provision of novel means for removing the occluded gases from the light sensitive material as it passes from the developing chamber and particularly in the manner in which the light sensitive material, as it travels along, is brought into contact with an arrangement of chemical devices which automatically remove the occluded gases from the light sensitive material.

Yet another object of my invention resides in the arrangement of the traveling feeding cords or belts with respect not only to the elements in the developing chamber, but also to the chemical devices for removing the occluded gases and also the suction apparatus in the ventilating chamber.

Still another object resides in the construction of the cabinet with a transparent wall for viewing the development of the material and in the arrangement of a shiftable delivery trough constructed and arranged to cooperate with the outlet discharge of the cabinet for delivering the developed light sensitive material to either side of the cabinet.

Yet another object of my invention resides in the arrangement of the spray pipe for producing a rather broad path or zone of falling drops of liquid developing medium, such as ammonia, whereby to provide a fairly wide gas evolving zone within the developing chamber and adjacent to which the light sensitive material is fed along and in a manner so as to preclude the wetting of the light sensitive material by the falling drops or particles of liquid developing medium.

Still another object of my invention resides

in the particular means and method whereby I remove the occluded gases from the light sensitive material.

These and other objects of my invention will be apparent from a perusal of the following specification when taken in connection with the accompanying drawings, wherein:

Figure 1 is a side sectional view of the preferred form of my present invention; and

Figure 2 is a perspective view of the under-side of one of the spray tubes.

Referring now to the drawings in detail, my improved invention comprises a proper support or base 2 upon which is mounted a cabinet 4 of substantially air-tight or gas-tight nature. This cabinet is preferably provided with a front wall 6 of transparent material, preferably of glass, whereby the operations going on within the cabinet may be viewed. In addition, the cabinet is provided with internal partitions 8, the first one being horizontal and joining a substantially vertical partition 10 having a basal horizontal portion 12 and a vertical portion 14 lying substantially parallel with wall 10, and in addition, a rearmost horizontal wall 16 is provided whereby these partitions form a preliminary chamber 18, a developing chamber 20, a degassing chamber 22 and a ventilating chamber 24. The front wall 6 of the cabinet is provided with a shelf or ledge 26 arranged opposite an inlet opening 28 extending slightly more than the width of the maximum width of light sensitive material which is to be fed within the cabinet. In addition, the cabinet is provided with a discharge opening 30 preferably located at the basal wall 32 and preferably at the rearmost portion of the cabinet.

Within the cabinet proper and within each one of the chambers thereof I locate a plurality of guide rolls for effecting either the interrupted or continuous feed of the light sensitive material through the developing cabinet. In the present instance I prefer to feed the light sensitive material, either in the form of relatively short sheets or in the form of continuous strips, in a continuous manner through the machine so that the light sensitive material, when fed in at the inlet opening, will pass continuously through the machine and will be discharged at the outlet opening 30. In order to accomplish this the various guide rolls within the cabinet and within the chamber are provided with a plurality of spaced apart grooves in which run cord or string belts. There are two sets of these cords and the light sensitive material is fed between the two sets and is carried by the travel of the opposed cords on the upper and lower faces of the light sensitive material through the cabinet. Referring now to chamber 18, it will be seen that within this chamber I locate two rolls 34 and 36. The space between these rolls is directly in line

with the inlet 28. The first set of cords 38, passes around the lowermost guide roll 36, thence it passes over and in contact with a liquid applying roll 40 likewise having a plurality of spaced apart grooves 42 therein. This roll 40 rotates in contact with a second roll 44 revolving in a container 46 of water so that the water is applied to roll 44, thence to roll 40 and thence to the under or light sensitive side of the light sensitive paper as it is fed along. Cord 38, after passing through the grooves of the roll 40, thence passes through an opening 48 in partition 10. This opening is provided with packing strips 50 to prevent the passage of developing gas out through the opening 48 while permitting the passage of feeding means therethrough. After passing into the developing chamber 20 this cord 38 then passes around another guide roll 52 located therein, thence downwardly along another guide roll 54 to the bottom of the developing cabinet 20 where it passes along a guide roll 56 and thence upwardly along another guide roll 58 from whence it passes to still another guide roll 60 located substantially at the top of the chamber 20. The belt then continues downward in contact with the guide roll 62 and thence around a lower guide roll 64 at which time the set of cords 38, pass out through an opening 66 in wall 14 into the degassing chamber where it passes around another roll 68 and thence upwardly around another roll 70, thence downwardly around another roll 72 thence upwardly around roll 74 and thence downwardly through opening 76 in partition 16 from which point the belt continues in its travel around rolls 78, 80, 82, 84, 86, 88, 90, 92 and 94 from which point cords 38 pass around a guide roll 96 located at the rearmost front part of the cabinet where the cords 38 then pass upwardly and through an opening 98 in the horizontal partition wall 8 from which point they again pass around the feed roll 36 in a continuous manner. In a similar way the set of cords 100 pass around the guide roll 38 at the inlet 28 portion of the cabinet and thence pass in contact with the grooved guide roll 40 in the preliminary chamber, thence through the opening 48 in wall 10, thence around the guide rolls 52, 54, 56, 58, 60, 62 and 64 in the developing chamber, thence through the opening 66 in the partition wall 14, thence around rolls 68, 70, 72 and 74 located in the degassing chamber, thence out through outlet 76 thereof, thence around guide rolls 78, 80, 82, 84, 86, 88, 90 and 92 and thence around a guide roll 102 located at the discharge outlet 30 of the cabinet and from which roll 102 the set of cords 100 pass upwardly through an opening 104 in the partition 16, whence the cords pass along through the degassing chamber and around a drive roll 106 and thence

through another opening 108 in the wall 14, thence through the upper portion of the developing chamber and thence through still another opening 110 in the wall 10 back to roll 34. The drive roll 106 is driven by means of a sprocket chain 112 running over a sprocket 114 on a shaft 116 carrying a worm-gear 118 meshing with a worm 120 on shaft 122 driven by a belt 124 from a motor 126 mounted on the rear of the cabinet. The shaft 116 and the driving mechanism is enclosed within a gas-tight housing 128 and the chain 112 passes through an opening in the rear wall of the cabinet. It will thus be seen that in the foregoing construction the two independent sets of cords travel together from the opposed rolls 34 and 36 at the entrance 28 of the cabinet and in spaced relation so that any light sensitive material which is fed through the opening 28 into the bite of the rolls 34 and 36, will be positioned between the upper and lower sets of cords 38 and 100 respectively and as these cords travel toward the rear of the machine, they will take with them the light sensitive material positioned therebetween. Thus the light sensitive material will be carried in the path hereinbefore set forth and will be finally discharged through the opening 30 at the bottom of the cabinet. By controlling the speed of rotation of the motor 126 or by either rotating it intermittently or in a continuous manner, the travel of the light sensitive material either in short sheet form or continuous strips, may be variably controlled.

In chamber 20 I propose a novel method of evolving or creating developing gas for developing the light sensitive material. In the present instance I have described ammonia gas as the developing agent but it must be understood that any type of developing gas is within the contemplation of my invention. In my present process I propose to subdivide the liquid ammonia into relatively small particles such as drops or a comparatively fine spray, and I propose to let this spray of liquid or drops of liquid fall through the air within the developing chamber 20 so that during their passages through the air, the relatively small particles of liquid ammonia, or the like, will give off developing gases and I propose to do this in a manner so as to prevent the liquid drops or spray from touching or wetting the light sensitive material so that the latter is developed in a dry manner and solely by the action of gases given off by the falling liquid particles. I further propose to re-capture the liquid spray or drops which fall to the bottom of the cabinet and re-convey them upwardly to the point from which they are released. In the present instance the preferred apparatus for carrying out my process consists in two or more spaced apart substantially oval pipes 130 and 132 which extend substantially the width of the develop-

ing chamber. The underside of these pipes I provide, as shown in Figure 2, with a zig-zag formation of relatively small holes or pits 134 whereby to provide a relatively wide path or zone of falling drops. I connect each one of the pipes 130 and 132 with distributing pipes 136 and 138 which, in turn, are connected to the bottom of an ammonia containing pan 140. These pipes 130 and 132 are preferably formed of glass or other rust-proof material which is not corroded by the action of ammonia. The holes or pits 134 are so small that the capillary attraction of the liquid holds it back so that it passes through these relatively minute nozzles drop by drop. As the drops are falling down through the air they give off ammonia. Thus the ammonia is generated more quickly than it would be by simply rising from a pool of ammonia. By breaking up the ammonia into relatively small bodies or particles or drops, it is more finely divided and evolves the ammonia gas much more quickly. The ammonia, as it falls through the air, is collected into pans 142 and 144 which, in turn, empties pipes 146 and 148 and is pumped back by means of pump 150 through a return pipe 152 emptying into the pan 140. Thus the ammonia which has fallen is re-circulated or pumped back for further use. It will be noted that by reason of the arrangement of guide rolls disposed so as to feed the light sensitive material close to but out of contact with the falling drops 154 and 156, the paper is not wetted while at the same time it is brought very close to the zone of evolution of the gases. It will also be noticed that the light sensitive material is carried inside and slightly parallel to the two paths of travel 154 and 156 respectively of the falling drops so that the paper is subjected to developing action both while going down and while going upwardly again, in other words, in two directions of its travel. Hence the traveling paper is substantially closed on two sides by a screen of developing gas so that the developing action is relatively rapid, particularly so when used in connection with the rolls 40 and 44 for applying a relatively thin film of water to the surface of the light sensitive material.

After passing from the developing chamber, the light sensitive material is carried in circuitous paths, running substantially parallel to each other, about the means for removing the occluded gases therefrom. In the present instance I propose to remove these occluded gases by the use of certain dry solid absorbents held in suitable containers and adjacent to which the light sensitive material passes. I prefer to use certain crystalline hydrated inorganic salts of certain metals and the preferred substances are the salts of the metals whose atomic weights are between 52 and 66, and including chromium,

manganese, iron, cobalt, nickel, copper and zinc. These, as well as certain others such as cadmium, mercury, magnesium, etc., which may be used, form addition or substitution products with ammonia, and when in the hydrated form have the water of crystallization replaced by ammonia of crystallization. These salts may be used in dry, solid form, and in the practical application the light sensitive material from which I propose to remove the occluded gases is passed over or relatively close to the absorbent used either by itself, or as an impregnant for such carriers as charcoal, which in itself has a well known gas absorbing action, pumice, kieselguhr, etc., powdered pumice gives very good results. The absorbent material gives better results when carried on one of the materials above noted than when used alone, since in the latter case the material has a tendency to powder and pack. In general the carrier is impregnated with about fifty per cent of its weight of absorbent material. This impregnation is carried on so that the material is deposited on the carrier in a crystalline condition from a solution of the metallic salt.

As a specific embodiment illustrated for the application of my invention, I propose to use powdered pumice impregnated with about sixty per cent of copper sulfate, pentahydrate; a known weight of 10-14 mesh pumice is placed in sufficient volume of a solution of blue-stone (technical copper sulfate) to give the ratio of one part of copper sulfate by weight to one and one-half parts of pumice. The solution is then boiled down with constant stirring until the salt has crystallized out in the pumice and is almost dry. The material is then spread out and allowed to dry in the air when it is screened on a 14 mesh sieve, thus removing the fines.

The percentage composition of the original mixture may vary from one part of copper sulfate with one part of pumice, to one part of copper sulfate with two parts of pumice. These ratios give the best compositions for all practicable purposes. In a composition of the first ratio, more material will be screened out as fines, while the second ratio gives somewhat less copper sulfate on the grains with a consequently slightly lower absorption value. Where longer life is desirable, a high impregnation may be used or one of the other absorbent materials may prove more valuable under the particular circumstances of any specific case.

Various considerations point to copper sulfate as a good general absorbent combining as it does ready availability and cheapness with its high absorption power. The following salts have given noteworthy results; zinc sulfate, nickel nitrate, ferrous sulfate, and cobalt chloride.

65 The above given method of impregnation

is merely by way of example since any method which will give the proper subdivision of the absorbent crystals or fragments, and the supporting and spacing of them for free access by the air and ammonia, is suitable in the preparation of the absorbents or filler mass. The method disclosed is however particularly adapted to the preparation of absorbents, consisting of crystalline salts.

The absorbents when in use are packed in a metal container, the latter having been coated with a covering of a protective paint to protect it from possible corrosion due to the ammonia or other gas or absorbent material.

In the apparatus for carrying out my process I provide two relatively deep and preferably rectangular-shaped containers the walls of which are formed as screens. These containers are illustrated in Figure 1 of the drawings at 160 and 162 and are located between the runs or two cord belts as they pass between the feed rolls 68, 70, 72 and 74. The absorbent material 166 is packed between the screen walls forming the containers and during the passage of the light sensitive material in close proximity to the screen walls of the containers, any occluded gases carried by the light sensitive material are removed by the absorbent action of the material.

A further advantageous use of the absorbent and the manner of removing the occluded gases resides in the fact that the ammonia after absorption by the materials described may be readily recovered by the simple expedient of exposing this used absorbent material to decreased pressure or increased temperature. The ammonia may be recovered while the absorbent is regenerated. It is also to be noted that the fact that the absorbed gas is readily given off in some cases under reduced pressure, shows that the absorption may be primarily a physical phenomenon.

The readiness with which the absorbents give up the absorbed gases under changed condition render them particularly valuable as it is only necessary to remove the absorbent and expose it to changed or altered physical conditions, that is, lower pressure or higher temperature, and the absorbed gas is given off and the absorbent material is regenerated and is available for further use.

After the light sensitive material has passed from the degassing chamber, it travels through the opening 76 which is likewise fortified with the packing strips and thence the light sensitive material passes in a devious path about the rollers 78 to 94 inclusive through the ventilating chamber. This chamber is opened at one end by means of a relatively small opening to the atmosphere and at the other end is connected to a conduit 168 having connec-

130

tion with an exhaust or fan 170 for sucking air through the ventilating chamber. This ventilating apparatus removes any possible residual trace of ammonia that may be left in the light sensitive material. At the outlet of the ventilating chamber opposite the feed rolls 94 and 102, I provide two spaced apart tongues directly at the bite of the rolls which serve as deflectors for deflecting the light sensitive material through the opening 30. At the bottom of the cabinet I provide a shiftable discharge trough consisting of a sheet metal or other support 172 having curled ends 174 and 176 and provided with an intermediate arm 178 pivoted as at 180 to the support 2. With this construction the trough 172 may be tilted either into full line position or into dotted line position so that in either position the light sensitive material 20 discharged from the opening 30, will be conducted around to the front or to the rear of the machine. Obviously other arrangements for selectively diverting the discharge feed of the material to various points may be utilized.

It will thus be appreciated that by reason of my present construction and particularly by reason of the process herein described, I very quickly and economically evolve developing gas from the liquid developing medium, such as liquid ammonia, and I have provided an apparatus for accomplishing development of light sensitive material in a minimum time while at the same time accomplish- 25 ing a very effective developing action.

By reason of the utilization of the spray or the breaking up of the liquid ammonia into relatively fine drops which fall through prescribed paths in the developing chamber, 40 evolving the developing gas during its fall through the air, I provide prescribed zones or areas of gas screens or paths adjacent to which I feed the light sensitive material and in the manner such that the material is not wetted by the falling liquid developing medium but is developed since it passes closely enough so that the evolved gases quickly act upon the light sensitive material. Furthermore, by reason of the relatively small nozzles 45 in the tubular pipes, the control of the rate of dropping of the liquid ammonia is accomplished since by reason of the capillary action of the liquid and the size of these tips or nozzles 34, the liquid is permitted to escape only drop by drop which thus subdivides the liquid ammonia into small enough 50 particles so that in passing through the air it will give off the gas at the desired rate.

It will also be appreciated that by reason 60 of the circulating system whereby the liquid ammonia is collected and returned to the upper reservoir, I am enabled to re-use the ammonia repeatedly.

It will also be evident that by reason of 65 my improved construction of a dry absorbent

for which the ammonia gas has particular affinity, I am enabled to provide self-contained means for removing the occluded gases which are so objectionable, and this means is of particular virtue in its present relation 70 since it may be quickly re-generated by further treatment so that the absorbent material may be repeatedly used. In some instances I propose to use this absorbent material without the further use of the ventilating chamber and the suction device but in the present device I prefer to use them in combination.

It is thought that the invention and numerous of its attendant advantages will be understood from the foregoing description, 80 and it is obvious that numerous changes may be made in the form, construction and arrangement of the several parts without departing from the spirit or scope of my invention or sacrificing any of its attendant advantages, the form hereinbefore described being 85 of a preferred embodiment for purposes of illustration.

I do claim herein either by itself or in combination with the developing apparatus, the 90 means for removing occluded ammonia gas, since the same is claimed in my co-pending application, Serial No. 259,751, filed March 7, 1928; nor do I claim herein the means for or method of premoistening the light sensitive material before it is subjected to the ammonia fumes in the developing compartment, nor the arrangement of the several compartments in the cabinet, since the same is set forth and claimed in my co-pending applications, Serial No. 248,745, filed January 23, 1928, Serial No. 282,792, filed June 4, 1928, and Serial No. 287,139, filed June 21, 1928.

Having thus described my invention what I claim as new and desire to secure by Letters Patent is:

1. The herein described process which consists in projecting relatively small portions or drops of a liquid developing medium capable of evolving developing gases through prescribed paths whereby to permit the evolution and dispersion of a developing gas in the neighborhood of said paths and passing light sensitive material relatively close to said paths whereby to expose the light sensitive material to the said gases but out of contact with the liquid whereby said light sensitive material will be developed by the developing gas given off by said moving particles without becoming moistened by the liquid.

2. In a developing apparatus, the combination of an enclosing cabinet, means therein containing a quantity of liquid capable of developing gases, means for spraying said liquid along a predetermined path through the air in said cabinet whereby to release developing gases in the neighborhood of said path, means for passing light sensitive material in a prescribed path relatively close 125

to the path of said spray but out of contact therewith whereby said material will be developed by the action of the gases given off by said falling liquid.

5 3. In a developing apparatus, the combination of a compartment, means containing liquid ammonia in said cabinet, means for discharging the liquid ammonia from said container in finely divided form so as to 10 permit the same to drop freely through the air in the compartment and means in said compartment for holding light sensitive material relatively close to said falling developing liquid but out of contact therewith 15 whereby said material will be developed by the action of the gases given off by said falling liquid and without wetting the same.

4. In a developing apparatus, the combination of means forming an enclosing cabinet, a container for liquid ammonia in 20 said cabinet, means providing a plurality of spaced apart nozzles or tits connected to said container and adapted to discharge drops of liquid ammonia therefrom whereby 25 said drops will fall in prescribed paths through and within the cabinet and traveling feeding means disposed within said cabinet and located so that its line of travel passes adjacent the path of the falling drops whereby 30 by the light sensitive material carried thereby will be developed by the action of the developing gases given off by said falling drops without coming in contact with the liquid.

35 5. In a developing apparatus, the combination of means forming an enclosing cabinet, a container for liquid ammonia therein, said container having means connected thereto and providing spaced apart spray 40 mechanisms each having a plurality of spaced apart tits adapted to drop the liquid ammonia drop by drop in prescribed zones spaced apart in the cabinet, feeding means within said cabinet comprising a traveling 45 carrier having its path of travel located close to the paths of the falling drops but out of contact therewith whereby light sensitive material carried along by said traveling carrier will be enclosed on both sides by the 50 falling drops and subjected to the dry action of the developing gas given off by said drops.

6. In a developing apparatus, the combination of an enclosing cabinet, a container 55 therein holding liquid ammonia, pipes branching from said container and terminating in relatively long tubes having spaced apart relatively small tits on the under side thereof to cause the liquid to fall drop by 60 drop, means adapted to collect said drops and means for turning said collected liquid ammonia upwardly to said container, a plurality of guide rolls in said cabinet, certain of said rolls being located above said nozzles and certain being located within the

paths of the falling drops, movable feeding means passing around said guide rolls whereby by the light sensitive material will be conveyed in two directions between the paths of the falling drops of liquid ammonia so 70 that said material will be developed by the action of the gases given off by the falling drops.

7. In a developing apparatus, the combination of means forming a frame, a container for liquid ammonia mounted in the frame, a liquid adapted to evolve developing gas carried in the container, said container communicating with a member provided along its length with a plurality of relatively 80 small spaced apart means for discharging liquid ammonia from the container drop by drop through the air and means for passing light sensitive material adjacent to the path of said dropping liquid but out of contact therewith.

8. In a developing apparatus, the combination of means forming a frame, a container for liquid ammonia mounted in the frame, a liquid adapted to evolve developing gas 90 carried in the container, said container communicating with a member provided along its length with a plurality of relatively small spaced apart means for discharging liquid ammonia from the container drop by drop 95 through the air and means for passing light sensitive material adjacent to the path of said dropping liquid but out of contact therewith, a receiver for the falling drops and means for pumping said recovered liquid upwardly to the container for the ammonia.

9. In a device of the class described, the combination of an enclosing cabinet forming a developing chamber, a relatively long tubular member in said chamber connected to a source of developing liquid, said tubular member having on its under side a plurality of relatively small tits or openings spaced apart transversely of the width of the tubular member and also spaced apart longitudinally of the tubular member to provide a zone of some thickness of falling ammonia drops adapted to give off developing gas during their fall.

10. In a device of the class described, the combination of a cabinet formed with a developing chamber, a relatively long tube in said chamber connected to a source of liquid ammonia, said tube having on its under side and longitudinally thereof relatively small openings arranged in substantially zig-zag formation to provide a zone of falling drops adapted to evolve ammonia gas.

11. In a device of the class described, the combination of a cabinet, a traveling carrier disposed in said cabinet for conveying light sensitive material therethrough, means for applying a thin film of water to said light sensitive material and means for dropping

5 relatively small particles of liquid ammonia through said cabinet in close proximity to the path of travel of the light sensitive material but out of contact therewith whereby said wetted developing material will be speedily developed by the action of the gas given off by the developing material.

10 12. In a device of the class described, the combination of a member forming a main cabinet, said member having a plurality of internal partitions forming a developing chamber and a preliminary chamber, an inlet opening in said preliminary chamber, a plurality of guide rolls disposed opposite the opening and other guide rolls mounted in said cabinet and in said developing chamber, a pair of endless cord conveyers passing around said guide rolls and adapted to travel together from the guide rolls at said inlet chamber through the preliminary chamber and through the developing chamber whereby the light sensitive material introduced between said traveling cords will be carried through said chambers, a water container in 15 20 25 30 35 40 45

said preliminary chamber, a roller mounted therein, a second roller rotating on the periphery thereof and adapted to be contacted by the traveling cords of the conveyer, said second mentioned roller being grooved to receive said cords therein, a tubular member in said developing chamber provided on its bottom with a plurality of spaced apart relatively small openings, means for connecting said tube with a source of liquid capable of evolving a developing gas whereby the liquid will be projected drop by drop from said relatively small openings and fall along a predetermined path in the developing chamber and give off developing gases, said tubular member being disposed so that said drops fall adjacent the path of travel of the feeding means whereby light sensitive material carried along said path of travel will be developed solely by the action of the gases given off by said falling liquid and will not be wetted.

50 55 60 65 13. In a device of the class described, the combination of means forming an enclosing cabinet and providing a developing chamber therein, an ammonia container located in the top of said chamber and a plurality of branched pipes depending from said chamber and terminating in spaced apart tubes extending substantially the width of the chamber, said tubes being provided on their under sides with spaced apart relatively small nozzles for discharging the liquid ammonia drop by drop through the chamber, receiving means for catching said drops, a pump for returning said caught liquid back to the container, a guide roll above each tube with the periphery of the guide roll located slightly within the innermost vertical plane of the tube, other guide rolls disposed between the path of falling drops and out of

70 75 contact therewith and a pair of traveling cords passing around the guide roll above one of said tubes, thence downwardly with in the path of falling drops from said tube toward the bottom of the receiver, thence upwardly inside of the path of falling drops of the other tube thence upwardly and over the top of said second tube and through said cabinet whereby light sensitive material carried by said conveying means will be subjected to the action of the evolved developing gas therefrom during two portions of its movement.

14. In a developing apparatus for light sensitive material, means for transporting the light sensitive material along a predetermined path and means for creating, adjacent said path, a spray of fluid of a type adapted to evolve gases for developing the light sensitive material whereby light sensitive material carried along said path may be developed by the gases evolved from said spray without becoming moistened by the liquid forming the spray.

80 85 90 In witness whereof, I have hereunto subscribed my name.

ADOLPH LANGSNER.
